[57] CLAIM

The ornamental design for an umbrella handle, as shown and described.

DESCRIPTION

FIG. 1 is a front elevational view of an umbrella handle showing my new design, the opposite side being a mirror image, the umbrella shaft shown fragmentarily; FIG. 2 is a right side elevational view thereof; FIG. 3 is a left side elevational view thereof, the umbrella shaft shown fragmentarily; and FIG. 4 is a top plan view thereof.
